US0D1071359S

(12) **United States Design Patent** (10) Patent No.: **US D1,071,359 S**
(45) Date of Patent: ** Apr. 15, 2025

(54) **HELMET**

(71) Applicant: **BOMBARDIER RECREATIONAL PRODUCTS INC.**, Valcourt (CA)

(72) Inventors: **Michael Roy**, Magog (CA); **Yvan Brousseau**, Granby (CA)

(73) Assignee: **BOMBARDIER RECREATIONAL PRODUCTS INC.**, Valcourt (CA)

(**) Term: **15 Years**

(21) Appl. No.: **29/928,435**

(22) Filed: **Feb. 12, 2024**

Related U.S. Application Data

(62) Division of application No. 29/826,426, filed on Feb. 11, 2022.

(57) **CLAIM**

The ornamental design for a helmet as shown and described.

DESCRIPTION

FIG. 1 is a perspective view taken from a front, left side of a helmet according to our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Throughout the Figures, where shown, the evenly dashed broken lines illustrate features that do not form part of the claimed design.

1 Claim, 7 Drawing Sheets
